UNITED STATES PATENT OFFICE.

CHARLES BEAUCHENE, OF LAKE LINDEN, MICHIGAN.

WRENCH.

No. 866,420.

Specification of Letters Patent.

Patented Sept. 17, 1907.

Application filed February 14, 1907. Serial No. 357,287.

To all whom it may concern:

Be it known that I, CHARLES BEAUCHENE, a citizen of the United States, and a resident of Lake Linden, in the county of Houghton and State of Michigan, have invented a new and Improved Wrench, of which the following is a full, clear, and exact description.

The object of the invention is to provide a new and improved wrench, which is simple and durable in construction and arranged to permit of conveniently and quickly adjusting the movable jaw for gripping nuts, pipes and other articles of different sizes, to securely lock the movable jaw in position on the stock after the adjustment is made, and to relieve the locking device of undue strain.

15 The invention consists of novel features and parts and combinations of the same, which will be more fully described hereinafter and then pointed out in the claims.

A practical embodiment of the invention is represented in the accompanying drawings forming a part of this specification, in which similar characters of reference indicate corresponding parts in all the views.

Figure 1 is a perspective view of the improvement; Fig. 2 is a side elevation of the same, parts being in section; and Fig. 3 is a cross section of the movable jaw section, taken on the line 3-3 of Fig. 2.

The shank or stock A of the wrench terminates at one end in a handle B, and at the other end in a fixed jaw C, operating in conjunction with the movable jaw D, 30 for gripping nuts, bolts and like articles. The jaws C and D are preferably provided at their opposite faces with teeth for securely gripping the article. The sliding motion of the movable jaw D in the direction towards the handle B is limited by a suitable stop E held 35 on the shank A.

The movable jaw D is provided with a recess D' adjacent to the inner side of the shank A, and into this recess D' fits a pawl F mounted to turn loosely on a pivot G held on the movable jaw D. A spring H secured to the movable jaw D in the said recess D', presses the heel of the pawl F, the inner end of which is provided with V-shaped teeth F' for engagement with correspondingly shaped teeth A' formed in the bottom of a groove A² arranged on the inner side of the shank A.

45 and extending in the direction of the length thereof. The pawl F is extended to the outside of the recess D', to form an integral finger piece F² provided on opposite faces with recesses F³, for engagement by two fingers of the operator's hand, to conveniently swing the pawl F outward, with a view to disengage its teeth F' from the teeth A' whenever it is desired to unlock the jaw D and to slide the same outward in the direction of the handle B, so as to release the nut, bolt or other arti-

cle gripped at the time. The teeth A' and F' are arranged to permit a free sliding of the jaw D towards the jaw C, so as to grip the article between the jaws, it being understood that when the article is thus engaged by the two jaws C and D, then the jaw D is automatically locked in place by the teeth F' of the spring-pressed pawl F engaging the corresponding teeth A'.

When it is desired to unlock and release the article, then it is only necessary for the operator to take hold of the finger piece F² with two fingers, and swing the pawl F outward, to move the teeth F' out of engagement with the teeth A', at the same time exerting an outward and downward pull on the finger piece F², so as to slide the jaw D towards the handle B and out of engagement with the article previously mentioned.

The outer end F¹ of the pawl F is segmental and abuts against the outer correspondingly shaped wall D² of the recess D' formed in the movable jaw D, so that when the article is gripped between the jaws C and D and the wrench is turned, then the pivot G of the pawl F is relieved of all undue strain, as the pawl engages with its under end the shank A and with its outer end the wall D² of the jaw D. The inner end of the pawl F fits against the side walls of the groove A², so as to hold the teeth F' thereof always in proper relation to the teeth A' of the shank A, and consequently a proper locking of the jaw D to the shank A is at all times secured.

The wrench shown and described is very simple and durable in construction, can be cheaply manufactured and readily manipulated to securely grip bolts, nuts and other articles of different sizes.

Having thus described my invention, I claim as new and desire to secure by Letters Patent:

1. A wrench comprising a handled shank having a longitudinal groove in its inner side and ratchet teeth in the bottom of the groove, a fixed jaw on one end of the shank, a slideable jaw on the shank and having a recess in its rear face, the said recess extending approximately parallel with the front face of the jaw and having a closed outer end, the wall which is curved, a pawl pivoted loosely and approximately at the center of its length in the recess of the said jaw, the pawl being of a thickness a little less than the width of the groove of the shank and having its outer end curved to correspond with the curved end wall of the recess and its inner end extending into the groove of the shank and provided with teeth engaging the teeth in the bottom of said groove, and a spring in the recess of the movable jaw for holding the teeth in the pawl in engagement with the teeth of the shank.

2. A wrench comprising a handled shank having its inner side provided with a groove extending in the direction of the length of the shank, the bottom of the groove being provided with ratchet teeth, a jaw fixed on the said shank, a jaw slideable on the said shank and having in its rear face a recess adjacent to the said grooved and toothed side of the shank, the recess extending approximately parallel with the front face of the jaw and having its outer

end closed, the wall of which is curved, a pawl pivoted loosely and approximately at the center of its length in the recess of the said slideable jaw, and having its outer end rounded off and its inner end extending into the groove of the shank and provided with teeth engaging the teeth in the groove of the shank, the pawl having at its outer face near the inner end an integral flat finger piece extending to the outside of the jaw and dished at both faces for engagement by the fingers of the operator, and a flat spring

secured at one end to the rear wall of the said recess and engaging with its free end the outer end of the said pawl.

In testimony whereof I have signed my name to this specification in the presence of two subscribing witnesses.

CHARLES BEAUCHENE.
